UNITED STATES PATENT OFFICE

2,410,296

INK FOUNTAIN

George Arthur MacDonald, Los Angeles, Calif.

Application July 5, 1944, Serial No. 543,548

2 Claims. (Cl. 120—59)

1

This invention appertains to new and useful improvements in ink stands and ink fountains, the principal being to provide a simple and conveniently usable ink fountain which is an improvement over the subject matter of my co-pending application Serial No. 489,919, for Writing set, filed June 7, 1943.

Another important object of the invention is to provide an ink fountain wherein, by removing a certain part, permits the filling of fountain pens in an easy and convenient manner.

Still another important object of the invention is to provide an ink fountain wherein means is provided to eliminate any tendency of ink to splash or escape from the container while the same is being filled.

Other objects and advantages of the invention will become apparent to the reader of the following description.

In the drawings:

Figure 1 represents a top plan view with the bottle removed.

Figure 2 is a vertical sectional view taken on the line 2—2 of Figure 1.

Figure 3 is a transverse sectional view taken on the line 3—3 of Figure 1.

Figure 4 is a fragmentary sectional view taken on the line 4—4 of Figure 1.

Figure 5 is an inside elevational view of the removable pen guide.

Referring to the drawings wherein like numerals designate like parts, it can be seen that numeral 5 denotes a container which may have a suitable cap. The container 5 has a box-like formation 6 protruding from a side portion thereof and having its bottom 7 substantially lower than the bottom 8 of the container 5. The bottom 8 is raised to clear any base upon which the container 5 is set and form a lower end seating flange 8' below said bottom.

Rising from the bottom 8 of the container 5 is a cup 9 having an internal circumferential shoulder 10 upon which the neck 11' of an inverted ink bottle 11 can rest, as is clearly shown in Figure 2.

Rising from the bottom 8 of the container 5 within the confines of the cup 9 is a post 12 which rises to a point substantially above the top of the cup 9, and this post 12 has an air by-pass channel 13 extending longitudinally thereon. The lower portion of the cup 9 has an outlet port 14 to permit the ink 18' to flow into the container 5 and into a well 15 which is located on the bottom 7 of the box-like structure 6, that is, at a level below the bottom 8.

The box-like formation 6 has a cover 16 from which an inclined pen guide of tubular form and

2

denoted by numeral 17 depends to open above the bottom 8 of the container 5. The well 15 for filling fountain pens is situated under the lower portion of the pen guide 17.

It can now be seen, that by removing the cover 16 of the box-like structure 6, the well 15 is exposed and a fountain pen can be inserted into a relatively deep pool of ink where it can be readily filled.

10 The ink bottle 11 is of the type represented in my co-pending application Serial No. 489,919, filed June 7, 1943, in which the neck 11' normally has a cork or other form of stopper 18, which is pushed into the bottle 11 when the bottle is inverted and the stopper pushed against the post 12. The threads 11" shown on the neck 11' are for the usual screw sealing cap, not shown.

Obviously, ink in escaping from the bottle and cup 9 will rise only to a level consistent with the top of the port 14 (see Figure 4).

20 While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. An ink fountain comprising a container having a bottom, a downwardly tapering cup on said bottom for receiving the neck of an inverted ink bottle therein, a shoulder in said cup above said bottom forming a seat for said neck spacing the neck above the bottom of the container, and an outlet port in one side of said cup between the bottom of the container and said shoulder for establishing the level of ink in the container.

2. An ink fountain comprising a container having a raised bottom, a downwardly tapering cup on said bottom for receiving the neck of an inverted ink bottle therein, a shoulder in said cup above said bottom forming a seat for said neck spacing the same above the bottom of the container, an outlet port in one side of said cup between the bottom of the container and said shoulder for establishing the level of ink in the container.

40 3. An ink fountain comprising a container having a raised bottom, a downwardly tapering cup on said bottom for receiving the neck of an inverted ink bottle therein, a shoulder in said cup above said bottom forming a seat for said neck spacing the same above the bottom of the container, an outlet port in one side of said cup between the bottom of the container and said shoulder for establishing the level of ink in the container, said container having a side opening therein rising from said bottom, an ink well forming side compartment at said side of the container in communication with the container by way of said opening and having a bottom below the level of the bottom of the container, a removable cover for said compartment, and a tubular pen guide inclining from said cover downwardly to the side opening in the container.

45 4. An ink fountain comprising a container having a raised bottom, a downwardly tapering cup on said bottom for receiving the neck of an inverted ink bottle therein, a shoulder in said cup above said bottom forming a seat for said neck spacing the same above the bottom of the container, an outlet port in one side of said cup between the bottom of the container and said shoulder for establishing the level of ink in the container, said container having a side opening therein rising from said bottom, an ink well forming side compartment at said side of the container in communication with the container by way of said opening and having a bottom below the level of the bottom of the container, a removable cover for said compartment, and a tubular pen guide inclining from said cover downwardly to the side opening in the container.

GEORGE ARTHUR MACDONALD.
